(57) **CLAIM**

The ornamental design for a sensory chew simulating a key, as shown and described.

DESCRIPTION

FIG. 1 is a front isometric view of a first embodiment of our new sensory chew simulating a key;

FIG. 2 is a rear isometric view of the invention of FIG. 1; FIG. 3 is a front elevation view of the invention of FIG. 1; FIG. 4 is a rear elevation view of the invention of FIG. 1; FIG. 5 is a top plan view of the invention of FIG. 1; FIG. 6 is a bottom plan view of the invention of FIG. 1; FIG. 7 is a right side elevation view of the invention of FIG. 1; and

FIG. 8 is a left side elevation view of the invention of FIG. 1;

FIG. 9 is a front isometric view of a second embodiment of our new sensory chew simulating a key;

FIG. 10 is a rear isometric view of the invention of FIG. 9; FIG. 11 is a front elevation view of the invention of FIG. 9; FIG. 12 is a rear elevation view of the invention of FIG. 9; FIG. 13 is a top plan view of the invention of FIG. 9; FIG. 14 is a bottom plan view of the invention of FIG. 9; FIG. 15 is a right side elevation view of the invention of FIG. 9; and,

FIG. 16 is a left side elevation view of the invention of FIG. 9.

The broken dash lines comprise claim boundaries. Neither the portions inside the broken dash lines nor the broken dash lines themselves form any part of the claimed invention.

1 Claim, 6 Drawing Sheets
